UNITED STATES PATENT OFFICE.

FREDERICK E. KALTE, OF LOS ANGELES, CALIFORNIA, ASSIGNOR TO RANDALL CONTROL AND HYDROMETRIC CORPORATION, OF LOS ANGELES, CALIFORNIA, A CORPORATION OF CALIFORNIA.

ELEVATOR-DOOR LOCK.

Application filed October 13, 1923. Serial No. 668,303.

To all whom it may concern:

Be it known that I, FREDERICK E. KALTE, a citizen of the United States, and a resident of the city of Los Angeles, in the county of Los Angeles and State of California, have invented a new and useful Elevator-Door Lock, of which the following is a specification.

This invention relates to a lock for elevator doors, either for the shaft or for the car, and more particularly to a lock that is especially adapted for horizontal doors that open in a vertical direction, as on freight elevators.

Elevator doors of this character especially are sometimes so constructed that a considerable amount of play from side to side in the door guides cannot be prevented. When locks of the usual kind are installed under such circumstances, there can be no assurance that they will operate properly, since the locking part may be considerably out of alignment upon closing movement of the door. It is one of the objects of my invention to correct this condition, and to ensure that the doors may lock under any adverse swaying movement.

In many types of locks it is required that upon operation they cause a control circuit to be made or broken, whereby it may be ensured that the car cannot be started until all of the doors are closed. It is still another object of my invention to provide this interlocking feature in a horizontal type of door, that is reliable in operation, and may be depended upon even when the doors are poorly fitted and have considerable play in their guides.

It is still another object of my invention to provide in general an improved form of elevator door interlock.

My invention possesses other advantageous features, some of which with the foregoing will be set forth at length in the following description, where I shall outline in full that form of the invention which I have selected for illustration in the drawings accompanying and forming part of the present specification. Although I have shown in the drawings but one form of my invention, I do not desire to be limited thereto, since the invention as expressed in the claims may be embodied in other forms also.

Referring to the drawings:

Figure 1 is a fragmentary view of an elevator door and lock in closed position, and embodying my invention, some of the parts being shortened to permit the use of a large scale, and the covers for the lock being omitted so as to show its structure more clearly;

Fig. 2 is a view of the lock and its co-operating bolt in a partly opened position;

Fig. 3 is a sectional view of the lock, taken along plane 3-3 of Fig. 2; and

Fig. 4 is a side elevation of the complete lock, with its covers in place.

In the present instance I illustrate the device embodying my invention as applied to a vertically movable, horizontally extending elevator door 11. This door is shown as arranged to cooperate with a lower door 12, the two doors meeting on a line 13 and arranged to move apart and to move together. These opening and closing movements of the doors may be effected in any well-known manner, either manually or by power. Guides such as channels 14 may be provided for the doors, and furthermore doors such as illustrated may be placed either at the shaft landings or on the cars themselves, or both.

Horizontal movement of the door 11 cannot be altogether prevented, and in order that this horizontal movement be compensated for, I arrange a locking member or bolt 15 for this door that has itself a substantially horizontal operative movement. In this way, the horizontal motion of the door 11 is ineffective to throw the bolt 15 out of alignment with its lock. This feature is of great importance, for it is evident that it is merely necessary to provide a variable extent of operative movement of the bolt 15 in order to take up the side play. For guiding the bolt at one end, a strap 16 appropriately fastened on the door 11 is provided. The operation of the bolt 15 is effected in such a way that it is resiliently or yieldingly urged to its closing position toward the right. One way in which this may be accomplished is by the aid of a weighted bell-crank lever 17, the handle end 18 having sufficient weight to urge it to the position shown in Fig. 1. The other end of the lever 17 is pivoted to the

bolt 15, as at 19. The lever 17 is pivoted on a stationary part of the door 11, as on a standard 20 fastened to the door lip. Furthermore, appropriate stops 21 and 22 5 are arranged to limit the movement of the lever 17, and thereby that of the bolt 15. In order to open the lock, it is necessary to rotate lever 17 in a clockwise direction and against the weight of handle 18. This rotation 10 may be performed either manually or by power. It is evident that bolt 15 will then be moved toward the left. The weight of lever handle 18 urges the bolt 15 to closing position, and causes a comparatively 15 large movement thereof if it be necessary for fully closing the lock.

The lock 23, comprising a hollow casing, is appropriately supported on a relatively stationary part of the car or of the shaft, 20 and has an opening 24 into which the bolt 15 is adapted to enter. The closing movement of door 11 being in a downward direction, an inclined guide or cam 25 is arranged on the lock 23 to serve to move the bolt 15 toward the left automatically as this movement of the door occurs, and thereby to permit it to snap into the aperture 24 on continued downward movement of door 11. The lower surface of the end of bolt 15 30 is purposely rounded off as at 26 so as to facilitate this cam action. The guide or angle 25 is preferably made from steel or other good wearing material. The relative positions of the bolt 15 and the guide 25 35 just before the bolt is urged to a position to permit it to enter aperture 24, are illustrated in Fig. 2. Furthermore, as shown in Fig. 4, covers 27 are preferably provided for the lock 23 so as to protect the interior 40 thereof. Upon opening movement of the door, the bolt 15 is out of alignment with the aperture 24, so that this bolt cannot snap into place until the door 11 is entirely closed.

45 It is oftentimes desirable to provide safety devices ensuring against starting the car unless all of the elevator doors are closed. This is accomplished by an interlock arrangement, whereby a control circuit 50 is arranged to be interrupted while the bolt 15 is withdrawn from the lock. This circuit may include a pair of stationary contacts 28 (shown most clearly in Fig. 3) supported preferably near the back of lock 23, as on the insulation board 29. These contacts are in the present instance shown as parallel bars in electrical connection with wires 30 passing into the lock through the conduit 31. Furthermore these bars 28 are 55 close enough together as to permit them to be bridged by a contact disc 32 which is the movable element of the circuit controller. This disc is supported on a tumbler 33 pivoted as at 34 on the inside of the lock, 60 and having a free position such that the

disc 32 is out of contact with bars 28, as shown in Fig. 2. This effect is produced by gravity acting on the tumbler 33, although of course other means may be utilized for this purpose. The disc 32 is resiliently supported on the rear face of the tumbler 33 so as to permit the disc to have some axial movement. This is accomplished by the aid of a post or screw 35 which is insulatingly supported on the tumbler 32. 70 Against the head of this post the disc 32 is urged by the compression spring 36. This spring permits the disc 32 to have considerable movement to accommodate itself to the surfaces of bars 28, and further assists in insuring that there will be ample compensation for the side play in the door 11.

The rotation of tumbler 33 in a counter-clockwise direction to close the contacts may be effected only when the bolt 15 enters the lock 23. For this purpose the tumbler 33 is located in the path of travel of the bolt 15, and opposite the aperture 24 in the lock. Both the bolt and the tumbler are provided with notches, such as 37 and 38, forming interengaging projections or fingers 39 and 40. Thus on closing the lock, the finger 39 on bolt 15 enters into the notch 38 and serves as a positive means for urging the lever or tumbler 33 to the right. On the other hand, when the lock is opened, the fingers 39 and 40 engage and serve positively in preventing the contacts from sticking. The projection 40 may also serve conveniently as a stop for the tumbler 33, as shown most clearly in Fig. 2.

It is evident that by the aid of the device disclosed, proper operation of both the lock and of the contacts is assured, in spite of the side movement of the door 11. Furthermore, it is evident that many of the advantages of this invention may be secured for vertical doors of the usual type, as well as for the horizontal type shown.

I claim:

1. In a lock for a horizontal elevator door, a horizontally movable bolt supported on the door, a lock casing having an aperture alining with the bolt only when the door is in closed position, said bolt having a large horizontal movement to compensate for variations in the horizontal distance between the door and the lock casing, a tumbler in the casing, a contact resiliently supported by the tumbler, and a cooperating stationary contact, said tumbler and bolt having interengaging parts, whereby horizontal movement of the bolt in and out of the aperture may serve to operate the contacts positively in either direction.

2. In a lock for a horizontal elevator door, a weighted lever supported on the door, a horizontally movable bolt connected to the lever and extending beyond the door, the arrangement being such that the horizontal

movement of said bolt may be comparatively large, a lock casing having an aperture and supported at the side of the door, the aperture alining with the bolt only when 5 the door is in closed position, an inclined guide supported by the casing and cooperating with the lower surface of the bolt end to move it against the force exerted by the weighted lever as the door is brought 10 to closing position, and thereby to permit it to enter the aperture in the casing, a weighted tumbler opposite the aperture and pivoted for movement in the casing about

a horizontal axis, a contact resiliently supported by the tumbler and a cooperating 15 stationary contact, said tumbler having a notch near the place where the bolt enters the casing, and arranged to accommodate a cooperating finger formed on the end of the bolt, whereby horizontal movement of the 20 bolt in and out of the aperture may serve to operate the contacts positively in either direction.

In testimony whereof, I have hereunto set my hand.

FREDERICK E. KALTE.
